METHOD OF MAKING ELECTRIC HEATING UNITS

Rudolf Brey, Coswig, Germany, assignor to Westinghouse Electric & Manufacturing Company, East Pittsburgh, Pa., a corporation of Pennsylvania

Application April 15, 1938, Serial No. 202,248
In Germany April 20, 1937

2 Claims. (Cl. 219—37)

My invention relates to electric heating units and more particularly to range surface units and the method of making the same.

Electric cooking hot plates are now known to the art in which a heating element is imbedded in insulating material between two cover plates of material capable of withstanding high heat. The cover sheets are provided with grooves which, for example, extend in the manner of a spiral or in back and forth windings, and are usually connected to each other by welding after the heating coil and its insulation are disposed therein. In hot plates of this type it is difficult to make the filling grainy insulating material so dense that it will efficiently transfer the heat produced by the heating coil to the cover sheets.

It is, therefore, an object of my invention to provide a method of making a hot plate or heating unit in which, after the filling in of the insulating material within the grooves of a grooved cover plate and the rigid attachment or welding of a second cover sheet thereto, a further or additional special impression is utilized for the purpose of making the insulating material a dense solid homogeneous mass which will efficiently transfer the heat produced by the heating coil to the cover sheets.

A further object of my invention is to provide a range surface unit having an efficient rugged compact heating unit which is formed from a plurality of cover sheets.

Other objects of my invention will either be pointed out specifically in the course of the following description of one form of system embodying my invention, or will be apparent from such description.

In the accompanying drawing:

Figure 1 is an exemplary embodiment of a range surface or cooking unit embodying my invention and illustrated in section, and

Figs. 2 to 7 illustrate the development and process of making the heating unit shown in Fig. 1.

Referring to the accompanying figures, I show a range surface unit comprising in combination a supporting frame or casing 16 and a heating unit 6. The heating unit 6 includes grooved cover plates 11 and 20, insulating material 9 and 10 and a heating element 13.

The heating conductor or element 13, as shown in Figs. 4 to 7, inclusive, is imbedded in a grainy homogeneous insulating mass or material 15 between the groove 12 of cover sheet 11 and the second cover sheet 20. The space below the cover sheets or heating unit 6 is enclosed by the sheet

metal housing or casing 16, and the conductors 18 which extend from plugs or terminals 22 of the surface unit 5 to the heating coils 13 are insulated so that they shall not be subjected to the heat of the heating unit 6. If desired, an insulating buttress 17 of ceramic material or a radiation plate 18, or both, may be arranged between the heating unit 6 and the conductors 19 to retard the downward radiation and conduction of the energy from such heating unit.

When making the heating unit 6, the upper grooved cover sheet 11 is inverted or positioned so that the groove 12 located therein extends directly downwardly. The groove 12 is then open at the top. Insulating material 10 is then positioned within the groove 12 so as to substantially fill it. A groove 14 is then pressed into the insulating material 10 as such material is pressed or compressed in any desired manner, as shown in Fig. 3. The heating coil or element 13 is then inserted or positioned within groove 14 as shown in Fig. 4.

The groove 14 and heating element 13 are then covered with additional insulating material 9. The additional material is placed over the insulating material 10 and coil 13 so as to extend above the surface of the cover sheet 11. The cover sheet 11 and insulating material 9 is then covered with the second cover plate 20. The cover plate 20 has a shallow groove 21 therein. The cover plate 20, after being positioned over the insulating material 9 in such a manner that groove 21 cooperates or registers with groove 12 to form an elongated passage, is rigidly connected to the cover plate 11, preferably by welding as shown in Fig. 6.

The insulating mass 15 including insulating material 9 and 10 which fills the hollow space or elongated passage formed by grooves 12 and 21, is then made considerably more dense by pressing down or flattening the groove 21. The groove 21 in cover plate 20 is flattened by such subsequent application of pressure substantially normal to plate 20 as indicated by the arrows in Fig. 6. During this operation the cover plate 20 is pressed into substantially a smooth flat surface plate as shown (inverted) in Fig. 7.

Fig. 7 illustrates a completed heating unit 6 with the grooves 12 of the cover sheet 11 extending upwardly. This is the preferred normal operating position of the heating unit. However, it is to be understood that the heating unit may be inverted and the flattened cover sheet 20 positioned on top so as to function as a flat surface cooking plate.

Various modifications may be made in the device embodying my invention without departing from the spirit and scope thereof, and I desire, therefore, that only such limitations shall be placed thereon as are imposed by the prior art and the appended claims.

I claim as my invention:

1. The method of making a heating unit embodying a grooved cover plate which includes, placing insulating material within the groove of the cover plate, positioning a heating element on the insulating material, placing additional insulating material within the grooves so as to cover the heating element and substantially fill the grooves, positioning a second plate upon said cover plate to cover the grooves, rigidly attaching the second cover plate to the cover plate, and applying pressure to deform portions of the second plate so as to compress the insulating material into a homogeneous mass.

2. The method of making a range surface unit embodying a grooved cover plate which includes, placing insulating material within a downwardly extending groove of an inverted cover plate, positioning a heating element within the groove and on said insulating material, placing additional insulating material within the groove to cover the heating element and extend above the level of the cover plate, positioning a second plate upon the cover plate and rigidly attaching it thereto, the second plate having a groove therein which will cooperate with the groove in the cover plate to form substantially an enclosed elongated passage, and applying pressure upon the second plate so as to flatten the grooves therein and compress the insulating materials into substantially a single solid homogeneous mass.

RUDOLF BREY.
